DESIGN FOR A LAWN MOWER HANDLE

George W. Davis, Richmond, Ind., assignor to G. W. Davis Corporation, Richmond, Ind., a corporation of Indiana

Application April 22, 1940, Serial No. 91,830

Term of patent 7 years

To all whom it may concern:

Be it known that I, George W. Davis, a citizen of the United States, residing at Richmond, in the county of Wayne and State of Indiana, have invented a new, original, and ornamental Design for a Lawn Mower Handle, of which the following is a specification, reference being had to the accompanying drawing forming a part thereof.

Fig. 1 is a front elevational view of a lawn mower handle showing my design;

Fig. 2 a side elevational view; and
Fig. 3 a section on line 3—3 of Fig. 1, on an enlarged scale.

I claim:

The ornamental design for a lawn mower handle, as shown.

GEORGE W. DAVIS.
